UNITED STATES PATENT OFFICE

119,592

DESIGN FOR A COOLER CABINET

Ralph E. Kruck, Springfield, Mass., assignor, by
mesne assignments, to Coca-Cola Company, a
corporation of Delaware

Application August 29, 1939, Serial No. 86,930

Term of patent 14 years

To all whom it may concern:

Be it known that I, Ralph E. Kruck, a citizen of the United States, residing at Springfield, in the county of Hampden and State of Massachusetts, have invented a new, original, and ornamental Design for a Cooler Cabinet, of which the following is a specification, reference being had to the accompanying drawings, forming a part thereof.

Fig. 1 is a front perspective view of the cooler cabinet showing my design;

Fig. 2 is a top plan view thereof;

Fig. 3 is a front elevational view;

Fig. 4 is a rear elevational view;

Fig. 5 is an end elevational view taken from the left; and

Fig. 6 is likewise an end elevational view taken from the right of the cooler cabinet as same is shown positioned in the other figures.

I claim:

The ornamental design for a cooler cabinet, as shown.

RALPH E. KRUCK.
